UNITED STATES PATENT OFFICE

2,607,628

WATER SYSTEM FOR DISHWASHING MACHINES

Jefferson L. Jones, Cambridge, Mass.

Application May 11, 1945, Serial No. 593,232

2 Claims. (Cl. 299—141)

1

My present invention relates to dishwashing or like machines and particularly to the delivery systems for the wash water of such machines.

As, in dishwashing machines, the wash water is re-circulated, it is necessary to cleanse the wash water delivery system at regular intervals. In spite of careful screening, such systems generally and the manifolds and spray devices in particular, become fouled with food particles and foreign matter. As a result, both to ensure the efficient operation of the machines and for sanitary purposes, the cleansing of the wash water delivery system is an essential service. Because of the construction of machines prior to my invention, such service was difficult as it required exterior disassembly of the machines.

In accordance with my invention, I provide a washing machine having a washing chamber in which there is mounted a dish support in spaced relation to the sides of the chamber. A wash water tank receives drainage from the washing chamber and pump controlled means, in communication with the tank, deliver wash water to the chamber.

Such pump controlled means includes a riser element supporting a manifold element in the washing chamber below the dish support and the elements are assembled together by a quick releasable connection. Connected to the manifold element, as by bayonet joints, are a plurality of spray devices disposed between the dish support and an adjacent side of the chamber and these devices have a plurality of orifices disposed to deliver spray against dishes on the support.

The nature of the connection between the riser and manifold elements depends to a considerable extent on the type of dishwashing machine. Where the dish support is a removable basket, the connection may be a joint of the bayonet type. Where the dish support is an endless conveyor, the connection is a sliding joint permitting the top of the manifold to be moved endwise from the machine to avoid the necessity of disconnecting the conveyor.

In accordance with my invention, the wash water delivery system of dishwashing machines may be easily and effectively serviced as the manifold elements and the spray devices may be readily removed from the machines as a unit and quickly disassembled for thorough cleansing.

In the accompanying drawings, I have shown illustrative embodiments of my invention from which its novel features and advantages will be readily apparent.

2

In the drawings:

Fig. 1 shows in cross section a dishwashing machine in accordance with my invention.

Fig. 2 is a section along the lines 2—2, of Fig. 1.

Fig. 3 shows, in side view, a manifold and spray device assembly.

Figs. 4, 5 and 6 are sections along the lines 4—4, 5—5, and 6—6, respectively, of Fig. 2.

Fig. 7 is a section along the lines 7—7, of Fig. 3.

Fig. 8 is a fragmentary side view of a modification of my invention, and

Fig. 9 is a fragmentary section along the lines 9—9, of Fig. 8.

At 10, in Fig. 1, I have indicated generally a dishwashing machine having in its base a wash water tank 11 disposed to receive drainage from the washing chamber, generally indicated at 12. The machine 10 has a cover 13, hinged as at 14 to permit the basket 15 for dishes, glasses and silverware to be placed in or removed from the washing chamber 12.

The basket 15 is supported in spaced relation to the side walls 16 and 17 of the chamber 10 by removable guide rails 18 seated on brackets 19 and 20 mounted on the side walls 16 and 17, respectively.

At 21, I have indicated a ledge removably supporting a scrap tray or trays 22 which serve to screen a substantial part of the food particles and foreign matter from the water draining from the chamber 12 into the tank 11.

The tank 11 has an overflow pipe 23 adapted to be connected to any suitable drain (not shown) and at 24 I have shown a screen for the intake 25 of the pump 26 which may be placed where shown or located at one end of the tank 11. The outlet 27 of the pump 26 is connected to a riser 28 located near the side wall 16 of the chamber 12 adjacent one of its ends.

At 29, I have indicated generally a manifold which consists of a pair of parallel arms 30 and 31 of substantially the length of the chamber 12 and interconnected as at 32 so that the manifold 29 is U-shaped. The arm 30, adjacent its junction with the manifold portion 32, has a depending annular port 33 dimensioned to receive within it the upper end of the riser 28. The riser 28 has a pair of spaced projections 34 disposed to enter L-shaped slots 35 in the port 33 and to interlock therein on partial rotation of the manifold 29 relative to the riser 28.

By this construction, the riser 28 supports the manifold 29 below the basket 15 with its arms 30 and 31 parallel to the sides of the chamber 12.

and with the arm 30 between the basket 15 and the side wall 16 as shown in Fig. 1. As the width of the manifold 29 is substantially less than the width of the chamber 12, the bayonet joint between the riser and the manifold may be readily released, after the basket 15 and the guide rails 18 have been removed, by turning the manifold 29 relative to the riser 28 thereby permitting the manifold 29 to be lifted from the machine 10.

Preferably mounted on the manifold arm 30 are 10 a plurality of spray devices, generally indicated at 36, extending upwardly between the basket 15 and the chamber side wall 16. The spray devices 36 have orifices 37 disposed to direct jets of spray against objects in the basket 15.

As may be most clearly seen in Figs. 3 and 7, each of the spray devices 36 consists of a tube 38 having at its lower end a sleeve 39 adapted to fit snugly over a tubular outlet port 40 on the manifold arm 30. Each sleeve 39 has L-shaped slots 41 disposed to receive projections 42 on each port 40 to establish a bayonet type of joint by which the spray devices 36 may be quickly and easily and securely attached to or removed from the manifold arm 30.

Preferably, I provide the upper end of each of the tubes 38 with a pair of projections 43 to enter L-shaped slots 44 in caps 45 to establish bayonet joint connections by which the caps 45 may be easily detached from the spray devices to permit them to be thoroughly cleansed.

The manifold arm 31 extends substantially through the middle zone of the chamber 12 and is substantially wider than the arm 30 but is of less thickness. The arm 31 is formed with a plurality of orifices disposed to direct jets of wash water upwardly against objects in the basket 15. The orifices comprise a series of centrally disposed slots 46 (see Figs. 2 and 6) and a series of marginally disposed slots 47 (see Figs. 2 and 5). The manifold 31 is of great advantage as it takes the place of a series of tubes, generally three or four in number. Such tubes are relatively difficult to remove and clean.

At 48 and 49 I have shown caps closing the ends of the arms 30 and 31 of the manifold. The caps 48 and 49 are substantially identical and for that reason only the cap 48 is shown in detail (see Fig. 4). The ends of the manifold arms are formed with transverse grooves 50 and the caps, which are open at one side, have ribs 51 so that they may be slid transversely into and out of a position anchored on the ends of the manifold arms.

I have not shown operating controls and other details of the dishwashing machine 12 as these may be conventional. I have shown at 52 the rinse water conduit having a pair of leaders 53 extending adjacent the side 17 of the chamber 12. The conduit 52 has an arm 54 extending transversely of the chamber 12 below the manifold 29 and the arm 54 includes a pair of leaders 55 extending substantially the length of the chamber 12 and disposed on opposite sides of the manifold arm 31. The leaders 53 and 55 have ports 56 disposed, respectively, to direct jets of rinse water against the sides of and upwardly against washed dishes in the basket 15.

In Fig. 8, I have shown a modification of my invention in which the washing machine generally indicated at 57 has a washing chamber 58 through which dishes, glasses, and the like are carried by a conveyor 59 trained over sprockets 60 and 61 and supported by tracks 62 and 63.

At 64, I have shown the riser as indicative of the wash water delivery system. The riser 64 has an elongated mouth 65 disposed below the track 63 and adjacent the side wall of the chamber 58. The mouth 65 has grooves 66 extending along its sides to receive inwardly extending ribs 67 on the manifold element 68 to establish a slideable interlock between the mouth 65 and the manifold element 68 so that the manifold element 68 may be slid endwise from or into the machine out of or into a position in which it is locked to and supported by the mouth 65 of the riser 64. The manifold element 68 has a series of tubular ports 69 (see Fig. 9) offset to support the spray devices 36 between the conveyor 59 and the adjacent side of the chamber 58.

My invention makes possible a simple and inexpensive construction by which manifolds and spray devices may be quickly and easily disconnected from the wash water delivery systems of dishwashing machines to permit them to be thoroughly cleansed.

What I therefore claim and desire to secure by Letters Patent is:

1. A unit for dishwashing or like machines, said unit comprising a manifold including a pair of spaced, parallel, hollow arms interconnected at one end, a detachable closure for the other end of each arm, a downwardly opening inlet port in communication with one of said arms, one of said arms having a plurality of upwardly opening spray ports spaced therealong, a plurality of spray devices having vertically aligned spray ports, and means detachably connecting said spray devices to the upper surface of said other arm with the ports of each spray device being disposed towards said ported arm.

2. A unit for dishwashing or like machines, said unit comprising a relatively long and narrow manifold including a compartment having an inlet port and a cover, said compartment and said cover including complementary interengageable portions enabling said cover to be removed from or attached to said compartment in an endwise direction, a plurality of spray devices having vertically aligned spray ports, and means detachably connecting said spray devices to said cover with their ports disposed towards one of its sides.

JEFFERSON L. JONES.
